UNITED STATES PATENT OFFICE.

DAVID P. DAVIES, OF RACINE, WISCONSIN, ASSIGNOR TO J. I. CASE THRESHING MACHINE COMPANY, OF RACINE, WISCONSIN, A CORPORATION.

AIR-STRAINER.

1,286,951.

Specification of Letters Patent. Patented Dec. 10, 1918.

Application filed February 15, 1918. Serial No. 217,370.

To all whom it may concern:

Be it known that I, DAVID P. DAVIES, a citizen of the United States, residing at Racine, in the county of Racine and State of Wisconsin, have invented certain new and useful Improvements in Air-Strainers, of which the following is a specification.

In the use of internal combustion engines applied to tractors and like propellers, especially for field work, the carburetors are subjected to dust conditions to such extent that they become clogged, and fine dust particles are carried therethrough into the cylinders, bearings and other parts of the motor, causing wear and consequent damage thereto. My object is to provide an efficient air strainer or moistener for cleansing the air so that dust will be separated therefrom and the air purified and moistened before it enters into the carburetor, thus obviating the difficulties and preventing the damage referred to, and it consists in certain details of construction and arrangements of parts which I have demonstrated in actual practice to be highly practical and effective, all as will hereinafter more fully appear.

In the accompanying drawing, forming a part hereof, Figure 1 is a central vertical sectional view of my improved strainer, and Fig. 2 is a horizontal sectional view taken on the dotted line 2—2 in Fig. 1.

In said drawing the numeral, 5, indicates the main cylindrical body of the strainer, having a conical bottom, 6, which bottom is provided with an outlet, 7, having a removable plug, 8, therein. An air inlet pipe, 10, extends upwardly through the body 5 and terminates in two branches, 11 and 12, being in effect a T pipe by which I am enabled to take in a sufficient outside air supply from opposite sides of the device. About said pipe 10 is a cylindrical member, 13, arranged in telescoping relation to said pipe, and at its lower end carries an air tight float, 14, extending circumferentially about the same. Projecting downwardly from the periphery of said float is a gauze ring, 16, which serves the purpose of breaking up air bubbles, as will be hereinafter more fully explained. Near the lower end of the body 5 and surrounding the inlet pipe 10 is a collar, 17, of any suitable arrangement, which acts as a stop for the float 14 when it descends to lowermost position, to prevent injury to the gauze ring 16 by contact with the inlet pipes

11, 12. I also provide a guide, 18, between said float cylinder 13 and inlet pipe 10, preferably in the form of a spider, so that air may flow therethrough during its circulation, and which is secured to said float cylinder 13 and the ring portion of which approximately contacts with said inlet pipe 10, and thus acts as a guide to direct the proper movement of said float cylinder and the float 14 associated therewith as the latter moves vertically over said inlet pipe.

Upon the main body 5 of the strainer, I secure a cover, 20, held in place by hook bolts, 21, or other suitable devices, about the inner edge of which cover is a reinforcing strip, 22, which laps the inner upper edge of the body 5 and serves as a guide when assembling these parts, and, in order to insure an air tight fit between them, a gasket, 23, is provided. The upper side of the cover is provided with a water filling plug, 25, and also an air outlet pipe, such as the elbow, 26, arranged to be connected with a carburetor. In concentric relation to said outlet pipe 26 I arrange a depending guide, 28, having a head, 29, which guide telescopes about the float cylinder 13, and, together with the guide 18, serves to maintain said cylinder in positive position during its upward and downward movement. The lower end of said guide 28 may be projected inwardly as at 30, or other suitable arrangement applied, for approximately contacting with said cylinder. Above the head 29 is an air chamber, 31, having openings in its wall, to which I apply gauze or other mesh material, 32^a for breaking up air bubbles, and secure to said air chamber 31 and guide 28, deflecting or baffle plates, 32, 33, for a purpose to appear. It will thus be seen that the cover embodies said depending guide, screening, deflectors, water inlet and air outlet all in a single assemblage, which may be readily removed and replaced in proper alignment with the float contained in the body of the strainer.

In the main body 5 of the strainer I provide a transparent inspection plate, 35, through which the amount of water to be contained therein may be determined, and, with which plate may be associated an indicator (not shown) if desired.

In the use of my improved strainer, as will be understood, the same is installed on a tractor and its outlet pipe connected with

the carbureter. Water is placed in the body portion through the filling inlet to the amount that practice requires and which can be determined through inspection plate 35. The mechanical suction of the motor draws the outside air through the branch inlet pipes 11, 12, and up through pipe 10 into the float cylinder 13, and, as the latter is closed at 19, the air is deflected downwardly therethrough and between the spaces in the spider like guide 18, passing along within the gauze ring 16, thence therethrough, and upwardly through the meshes 32^a and out through the pipe 26 to the carbureter, the line of passage of the air being clearly indicated by the arrows in Fig. 1. In this manner any extraneous matter (such as grit or fine dust particles) mixed with the air becomes arrested when reaching the water and is caused to be precipitated therein, while the air has become separated therefrom and washed. The movement of the air is impeded by the screen 16 through which it passes, which has the effect of breaking up any bubbles which may contact therewith and the separation of dust which may be surrounded by globules of air. As a further safeguard for separating dust particles, the upper screens 32^a are provided which will exclude any small amount of grit that may be carried thus far. As will be understood, the accumulated sediment in the conical bottom of the strainer may be readily drained therefrom through the outlet pipe 7.

35 In practice it is desirable only to moisten the air passing through the strainer, as any small amount of water drawn into the carbureter will be injurious to the fuel vaporized thereby. I have found that the suction of the engine under some circumstances has the effect of drawing water from about the float and up along the inner wall of the strainer body 5, and also along the guide 28, to an appreciable extent, and to prevent such 40 water from passing through the upper meshes 32^a with the air, I provide the deflecting plates 32, 33, which have a deflecting action upon such water, and any portion thereof in the nature of spray or drops which

become deposited upon the deflectors drips 50 off to be returned to the main water supply.

I claim as my invention:

1. In an air strainer, a main body terminating in a conical bottom, a plurality of air inlets in the lower portion of said body 55 communicating with an air inlet extending into said body, a screened float surrounding said air inlet, a spider-shaped guide between said inlet and float, a stop beneath said float to limit its range of descent, a cover for 60 said body embodying a water filling inlet and an air outlet, a screen in said cover through which air passes, and a deflector to prevent fluid from passing through said screen and outlet. 65

2. In an air strainer, a body portion, an air inlet pipe extending thereinto, a vertically movable float over said pipe, a guide between said pipe and said float, a depending cylindrical guide about said float, 70 screens in the upper end of said latter guide for preventing the passage of dust particles, and deflectors associated with said guide for preventing water from entering said screens.

3. In an air strainer, a body portion embodying an air inlet and a float, and a cover 75 for said body comprising a depending guide adapted to be positioned over said float, an air chamber over said guide embodying a screen, a water deflector associated with the 80 upper end of said guide, and an outlet pipe leading from said air chamber.

4. An air strainer comprising a cylindrical body having a conical bottom, air inlet pipes in the lower portion of said body, a 85 central air inlet communicating with said pipes, a float telescopically arranged over said central inlet, a guide between said float and inlet for limiting the lower movement of said float, a cover for said body, and 90 transparent means in said body for inspection of the interior thereof.

In testimony whereof I affix my signature in the presence of two witnesses.

DAVID P. DAVIES.
